UNITED STATES PATENT OFFICE.

JAMES TOTHAM, OF NEW HAVEN, CONNECTICUT, ASSIGNOR TO THE PECK BROS. & COMPANY, OF SAME PLACE.

COMBINATION SUPPLY AND WASTE FIXTURE FOR WASHBASINS.

SPECIFICATION forming part of Letters Patent No. 553,699, dated January 28, 1896.

Application filed July 22, 1895. Serial No. 556,722. (No model.)

To all whom it may concern:

Be it known that I, JAMES TOTHAM, of New Haven, in the county of New Haven and State of Connecticut, have invented an Improvement in a Combination Supply and Waste Fixture for Washbasins; and I do hereby declare the following, when taken in connection with the accompanying drawing and the letters of reference marked thereon, to be a full, clear, and exact description of the same, and which said drawing constitutes part of this specification, and represents a broken view in vertical section of a fixture constructed in accordance with my invention.

My invention relates to an improvement in combination supply and waste fixtures for washbasins, the object being to produce a simple, compact, durable and effective device constructed with particular reference to convenience of assemblage and attention and repair.

With these ends in view my invention consists in a combination supply and waste fixture having certain details of construction, as will be hereinafter described, and pointed out in the claims.

In carrying out my invention I employ a removable cap A, the interior space of which forms a chamber A' for the horizontally-arranged valve B, which is adjustably attached to the outer end of a valve-stem B', the inner end of which is vertically perforated to receive a crank-pin C, depending from the outer end of a horizontally-arranged crank C', the inner end of which is secured to the vertically-arranged spindle C², the extreme upper end whereof is furnished with a horizontal handle C³. The valve B has bearing upon a valve-seat D, formed in the arm D' of a four-armed coupling-head, the hollow center of which is intersected by the passages formed in its respective arms. The depending arm D² of the said head is threaded for the application of a packing-nut E, which secures to the head the inner end of the tail-pipe E, to the outer end of which the inlet-pipe E² is attached. The inwardly-extending arm D³ of the head is threaded for the application of a packing-nut F, which contains an expandible packing-ring F²; and which secures to the head the lower end of the adjustable supply

tube F', the upper end of which is secured by a packing-nut F², containing an expandible packing-ring F³, to the lower end of a short vertically-arranged pipe F⁴, extending through the basin-slab G and terminating at its upper end in the chambered head H of the spout, which is itself not shown. It will be understood that by loosening the packing-nuts F and F² the pipe F' may be adjusted as desired, one end moving back and forth in the arm D³ and the other in the tube F⁴. The upwardly-extending arm D⁴ of the chambered coupling-head is externally threaded for the application of the lower end of a long stuffing-box I passing upward through the basin-slab G and secured therein by the nuts I' and I². The spindle C² before mentioned has bearing in the said stuffing-box and also in the nut I'. The said arm D⁴ is chambered for the reception of a sleeve J, the lower end of which impinges upon two packing-washers j j, which rest upon a beveled annular packing-rib c, formed at the lower end of the spindle C², for the prevention of the passage of any water out of the chambered coupling-head and upward around the spindle.

It will be understood that the construction above described is duplicated on the other side of the chambered spout-head H, the construction on one side being for hot and the other for cold water.

The chambered spout H before mentioned has mounted in center a vertically-movable waste-pipe K, which may be of any approved construction and does not need particular description or illustration, inasmuch as the part is well known.

It will be readily seen that by removing the cap A the valve B is exposed for adjustment, renewal or repair, thus making my improved construction very convenient, inasmuch as the valves require more attention than any other part of the fixture. Furthermore, I am enabled by my construction to assemble the whole device before the application and adjustment of the valve, which may then be done to a nicety, whereas in prior constructions of this class it has been necessary to adjust the valve prior to or during the assemblage of the parts. Again, by removing the handle C³ from the spindle C² and removing

the nut I² and the packing-nut F² the chambered coupling-head and the parts connected with it may be readily drawn away from the basin. Again, by the coupling provided for 5 the ends of the bent supply-tube F' the same is self-accommodating in position, so to speak, to the positions assumed by the other parts.

It will be understood that in the use of the device the water enters the fixture through 10 the inlet-pipe E² and tail-pipe E', and thence through the arm D² of the chambered head into the chamber A' within the cap A to the valve B, which stops its further progress through the fixture. When, however, the 15 valve is moved outward into the cap and away from its seat by the manipulation of the handle C³, the water rushes around the valve through its seat and through the central portion of the chambered four-armed head into 20 the adjustable supply-tube F', from which it enters the chambered spout-head H, from which it is delivered into the basin through the spout, which is not shown.

It is apparent that in carrying out my invention some changes in the construction 25 shown and described may be made, and I would have it understood that I do not limit myself thereto, but hold myself at liberty to make such changes and alterations therein 30 as fairly fall within the spirit and scope of my invention.

Having fully described my invention, what I claim as new, and desire to secure by Letters Patent, is—

35 1. In a combination supply-and-waste fixture for wash-basins, the combination with a chambered spout-head mounted in the basin-slab, of a stuffing-box also mounted in the basin-slab and depending therefrom, a long

spindle extending through the said box, a 40 handle applied to the upper end of the spindle, a four-armed chambered coupling-head having one of its arms connected with the depending end of the stuffing-box by which the said coupling-head is supported below the 45 basin-slab, a supply-tube connection between the said spout-head and one arm of the coupling-head, an inlet-tube connection with another arm of the head, a valve having bearing in the other arm of the head, connection between the said valve and the lower end of the spindle which enters the head through the arm thereof by which it is connected with and supported by the stuffing-box, substantially as set forth.

2. In a combination supply and waste fixture for wash-basins, the combination with a chambered spout-head mounted in the basin-slab, of a four-armed chambered coupling-head depending from the basin-slab, an adjustable supply-tube having slip-joint connection between the said heads, an inlet tube connected with another arm of the head, a valve having bearing in another arm of the head, a removable valve-cap applied to the 65 arm last mentioned over the valve, and removable for exposing the same, a spindle passing through the other arm of the head and extending upward through the basin-slab, and provided at its upper end with a 70 handle, substantially as set forth.

In testimony whereof I have signed this specification in the presence of two subscribing witnesses.

JAMES TOTHAM.
